United States Patent Office

Des. 188,301
Patented June 28, 1960

188,301

RESPIRATOR FOR ADMINISTERING OXYGEN AND OTHER GASEOUS MATERIALS

James C. Doak, Westlake, Ohio, assignor of one-fourth
to Walter S. Sutowski, Brecksville, one-fourth to Fred
J. Mingo, Westlake, and one-fourth to Francis B.
Douglas, Shaker Heights, all of Ohio

Filed Apr. 25, 1958, Ser. No. 50,629

Term of patent 14 years

(Cl. D83—1)

Fig. 1 is a front perspective view of a respirator for administering oxygen and other gaseous materials showing my new design;

Fig. 2 is a rear perspective view thereof, the side of the mask portion not shown being substantially like the side which is shown, and

Fig. 3 is a bottom plan view thereof.

I claim:

The ornamental design for a respirator for administering oxygen and other gaseous materials, as shown and described.
